GOOGLES

Charles Fischer, New York, N. Y.

Application February 25, 1937, Serial No. 127,591

3 Claims. (Cl. 2—14)

The invention relates to improvements in goggles and has particularly to do with that type of goggle used by aviators, drivers of racing automobiles, motor boats or any other apparatus where a high speed is maintained.

The present invention has to do with ventilating means for goggles and has for one of its objects to provide a ventilating arrangement, whereby fogging of the inner surface of the lens members and, consequent, blurring of the vision of the wearer, is avoided.

It has been found in practice that when the aviator's head is placed in some unusual position, either due to his own movement or movement of the plane, the ventilating means will defeat their own purpose and cause the lens members to fog. In accordance with the present invention it is impossible for this annoying and oftentimes dangerous condition to exist.

This application is renewal in part of my abandoned application, Serial No. 622,200, filed July 13, 1932.

Other objects and advantages of the invention will become apparent as the specification proceeds. Referring to the drawing forming a part thereof:

Fig. 1 is a front elevation of the goggle embodying the improvements of the present invention with parts broken away and parts in section;

Fig. 2 is a cross-sectional view taken on line 2—2 of Fig. 1;

Fig. 3 is a fragmentary elevation showing one of the air-entraining tubes;

Fig. 4 is a fragmentary sectional view taken on line 4—4 of Fig. 3;

Fig. 5 is a fragmentary elevation showing the air inlet orifices in the frame;

Fig. 6 is a perspective view of a modified form of an air-entraining tube; and

Fig. 7 is a perspective view of a throttle member for the inlet of the air-entering tube.

The goggle includes a pad 10 composed of soft rubber, provided with eye-openings 11, and adapted to efficiently and comfortably conform to the face of the wearer. Surrounding the eye openings and secured to the pad are light metal frames 12, hinged together at 13, and adapted to carry the lens members 14. The frames may be split to permit of the ready insertion or removal of the lens members and pad and when so split they are provided with clamping means indicated at 15. If desired the body of the frame may be one piece, a clamping frame utilized to hold the lens in position, and the pad sewed or otherwise secured to the frame.

The lower wall of each frame is punched to provide a plurality of inwardly depressed portions 20 and orifices 21, the latter being adapted to serve as air inlets (see Figs. 1, 2 and 5). The depressed portions 20 rise gradually toward the front of each frame and form hoods which serve to direct air forwardly toward the lens carried in each frame.

The upper wall of each frame is also punched to provide an outwardly pressed portion or hood 10 22 and a vent 23 (see Figs. 2 and 4). The vent 23 in each frame communicates with the passage ways 24 of an air-entraining tube 25 carried on the outer surface of each frame.

Each air-entraining tube is provided with an air inlet 26 and an outlet 27. The inlet is in the forward part of the tube and opens outwardly and is formed by having a part of the forward end adjoining front wall cut away. The outlet 27 is in the rear part of the tube and opens inwardly and is formed by having a part of the rear end and adjoining lower wall cut away. This construction is of primary importance as it always insures against any possibility of the air entering the outlet instead of the inlet, regardless of the position of the head of the wearer, and thus interfering with the proper functioning of the ventilating system. The cross-sectional area of the passageway 24 preferably increases from its inlet to its outlet end. The outside air passes at 20 high velocity through this passage 24 and entrains the air in the eye cup and carries it through the outlet of the passage.

A modified form of entraining tube is illustrated in Fig. 6. As in the tube previously described, part of the forward end and adjoining front wall is cut away to provide an inlet 26a. At its other end the tube is bent to provide a rearwardly extending horn, the mouth of which serves as a rearwardly facing outlet 27a.

If desired means may also be provided for controlling the admission of air to the inlets of the entraining tube to regulate the flow of air through the eye cup.

These means comprise a throttle member 45 movably mounted on each frame. As shown in Fig. 7, each throttle member comprises a flat plate 30, which, at its forward end is turned up to provide the vertical plate 31. The vertical portion 31 can be used to partially or entirely block the inlet of 50 the entraining tube of a frame. The throttle is preferably pivotally mounted on each frame by means of a pin 32 which is passed through the upper surface of each frame. When the throttle member is open and it is desired to diminish the 55

flow of air through the goggle, the throttle is swung into position over the inlet openings of the tubes, the vertically extending plates 31, serving as a finger-piece, whereby the throttle can be easily reached and manipulated.

5 Jets of air entering the goggle through the orifices at 21 will be deflected forwardly toward the lens members of the frames and will not strike directly against the face and eyes of the wearer. Hoods 20, adjacent the orifices, also prevent the entry of rain, dirt, or other particles to the interior of the goggle. The air admitted is drawn through the goggle and discharged through vents 23 by the passage of air through 10 the entraining tubes, with which the vents communicate. The arrangement of the tube outlets to face rearwardly insures the unimpeded discharge of air from the goggle and the throttle members permit the flow of air through the 15 goggle to be regulated. Air can thus be constantly circulated through the goggle in a regulated and unretarded stream and condensation on the inner surface of the lens members and consequent, fogging or blurring of vision, is avoided.

20 25 It will be understood that, in carrying the invention into practice, changes may be made in the improvements, described, without departing from the principle thereof.

I claim:

30 1. Means for ventilating goggles comprising, a metal frame formed with inlet orifices in its lower wall, hoods in the frame adjacent the orifices for directing air toward the front of the frame, a hooded vent in the upper wall of the frame, and an air-entraining tube of U-shaped cross-section 35 mounted on the upper wall of the frame, the air-entraining tube having an inlet in the forward part thereof which opens outwardly, said inlet being formed by slabbing off said tube from the median line thereof to a point along the front

5 wall of said tube so that part of the forward end and adjoining front wall of the tube are cut away, and an outlet in the rear part of the tube which opens inwardly, said outlet being formed by slabbing off said tube from the median line thereof to a point along the lower wall of said tube so that a part of the rear end and adjoining lower wall of the tube are cut away, the frame vent communicating with said air-entraining tube.

10 2. Means for ventilating goggles comprising, a metal frame formed with inlet orifices in its lower wall, hoods in the frame adjacent the orifices for directing air toward the front of the frame, a hooded vent in the upper wall of the frame, an air-entraining tube mounted on the upper wall of the frame, the air-entraining tube having an inlet in the forward part thereof which 15 opens outwardly and an outlet in the rear part thereof which opens inwardly, the frame vent communicating with said air-entraining tube, and a throttle member pivotally mounted on the frame adjacent the tube inlet, said member being operable to close or open the tube inlet.

20 25 3. In a goggle combination provided with a means for ventilating goggles comprising a metal frame formed with inlet orifices in its lower wall, hoods in the frame adjacent the orifices for directing air currents toward the front of the frame adjacent the lenses, a hooded vent in the upper 30 wall of the frame, an air-entraining tube covering the said hooded vent and in operative relationship therewith, the said entraining tube having an inlet in the forward part thereof which opens outwardly in a direction away from the face of the wearer, and an outlet of greater cross section than the said inlet, the said outlet being directed rearwardly toward the face of the wearer and in opposite direction to the said inlet.

CHARLES FISCHER.
